(57) **CLAIM**

The ornamental design for a case for electronic device, as shown and described.

DESCRIPTION

FIG. 1 is a front perspective view of a case for electronic device showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a rear perspective view of the case with a support leg extended;

FIG. 10 is a front exploded view of the case, showing an inner shell, the support leg, and an outer frame of the case;

FIG. 11 is a rear exploded view of the case, showing an inner shell, the support leg, and an outer frame of the case;

FIG. 12 is a front perspective view of the inner shell of the case;

FIG. 13 is a rear perspective view of the inner shell of the case;

FIG. 14 is a front perspective view of the support leg of the case;

FIG. 15 is a rear perspective view of the support leg of the case;

FIG. 16 is a front perspective view of the outer frame of the case; and,

FIG. 17 is a rear perspective view of the outer frame of the case.

The dashed broken lines in the drawings depict portions of the case for electronic device that form no part of the claimed design. The dash-dot broken lines define the boundaries of the claim that form no part of the claimed design.
